UNITED STATES PATENT OFFICE.

ELIJAH WARNE, OF EASTON, PENNSYLVANIA, ASSIGNOR, BY DIRECT AND MESNE ASSIGNMENTS, TO THE WARNE CONCENTRATOR AND SEPARATOR COMPANY.

SEPARATOR AND CONCENTRATOR FOR ORES, &c.

SPECIFICATION forming part of Letters Patent No. 258,331, dated May 23, 1882.

Application filed July 2, 1881. (No model.)

To all whom it may concern:

Be it known that I, ELIJAH WARNE, of Easton, Northampton county, Pennsylvania, have invented certain new and useful Improvements 5 in Separators and Concentrators for Ores and other Materials, of which the following is a specification.

My invention relates to machinery for separating ores and other materials by the dry process. I separate the mass of material by gravity into sub-groups, each composed of particles of unequal size, but substantially equal weight, and I subsequently separate the particles of each group according to size by a screening 15 process. It is not new, broadly considered, to employ this process of separation; but in order to effect accurate and well-marked separation, and also in order to adapt the machinery to effect this result upon ores and materials of 20 various kinds, it becomes necessary to render the parts capable of nice adjustment, so that they may be set or adjusted according to the requirements of the work and the nature of the material operated on.

25 I make use, as has heretofore been the case, of an air-blast or forced air-current for putting the material to be acted on in motion, so that its constituent particles may have opportunity to drop according to their different weights.

30 In doing this, however, I force the material by means of air through a nozzle, (in which the air bears with equal pressure upon the mass,) from which it suddenly emerges into an exhaust or separating chamber, where it is relieved to a great extent of the air-pressure, the chamber being provided with air-admitting 35 openings at all suitable points, which are adjustable to regulate the incoming of the surrounding atmospheric air. The particles which under these conditions are blown out from the nozzle fall, according to their weight, upon the floor of the chamber, provided with pockets or 40 openings, into which the particles fall. The heaviest particles fall in the pockets nearest 45 the nozzle, and so on. The pockets are adjustable in size in a direction lengthwise of the chamber, or at right angles to the current which passes over them, and can be set or adjusted to a nicety independently of one an-

other, so as to each receive particles of predetermined weight. For instance, the first pocket can be set to receive particles weighing one grain and upward, the next to receive those weighing between a grain and a half-grain, and so on. Owing to the adjustability of the pockets, the subdivision may be carried to a fine 55 point, and the material can be divided into as many sub-groups as desired.

The nature of my improvements and the manner in which the same are or may be carried into effect can, however, best be explained and understood by reference to the accompanying drawings, in which—

Figure 1 is a plan of a machine or apparatus embodying my improvements. Fig. 2 is a side 65 elevation of the same. Fig. 3 is a section on line 3 3, Fig. 1. Fig. 4 is a section on line 4 4, Fig. 3. Fig. 5 is a section on line 5 5, Fig. 3.

The granulated ore or other material is fed to a power-driven rotating screen, A, through 70 the meshes of which pass those particles which are not above the desired size. The large pieces pass off from the end of the screen into a spout, A', whence they are discharged from the apparatus. The particles which pass through the 75 meshes of the screen fall into an inclined chute, A², which conveys them into the feed-hopper B. This hopper, when the machine is in operation, is kept full, so as to prevent upward 80 passage of air through it. The feed of the ore from the hopper is regulated by a power-driven feed screw or worm, B', which fills the lower cylindrical discharge end of the hopper and prevents the downward passage of the ore, except as to those particles which, during its rotation, are carried down positively by its spiral 85 flange or thread. The particles thus fed along by the screw fall therefrom into the passage or tube a, whose shape in vertical and horizontal section is shown plainly in Figs. 3 and 5. The 90 passage at its rear expands into the air-chamber of a blower or air-forcing apparatus, C, of any suitable type. It also at this point inclines upward for some distance, in order to prevent possible backflow of ore dust or particles, which might choke the blower. In front 95 of the point where the ore enters it it again expands, so as to form a flattened fan-like nozzle.

- zle. The ore which falls into this passage is by the air-blast driven in a mass through the passage and blown with force from the nozzle end. I prefer on some accounts to mount on 5 the screw-shaft, below the feed thread or worm, a flat disk or plate, a^2 , on which the ore can fall. The ore in this position is more favorably placed to be effectively acted on by the air-blast.
- 10 In order to regulate at will the blast according to the conditions of the work and the nature of the material operated on, I provide the air-inlet of the blower with a gate or door, a^2 , which can be opened more or less, so as to 15 regulate the air-supply. The air, together with the material driven by it, emerges from the nozzle into a chamber, D' , in which the granulated material, although still carried along by the air and by the impetus acquired by it in its forced 20 passage through the nozzle, is relieved from pressure to a great extent, so that the particles are at liberty to fall upon the floor of the chamber by force of gravity, this taking place at points more or less remote from the nozzle, 25 according to the weight of the particles. The chamber should be so formed and arranged that it will be in more or less free communication with the outside air, as may be required. To this end I form in its sides and top openings 30 b at various points as large as required, and provided with doors or sliding covers, by which the size of the openings may be regulated. For the same purpose I close the far end of the chamber by a door, c , which can be 35 opened more or less, as required, in order to regulate or modify the air blast or current.
- In that portion of the floor of the chamber, 40 over which the material is blown I form a series of pockets or openings, D , crosswise of the current. These pockets receive the particles as they fall. It is not new with me, broadly considered, to provide such pockets or openings for this purpose; but with pockets as heretofore arranged I have found it impracticable to 45 effect accurate separation into sub-groups of differing weights, while, even if separation be effected with approximate accuracy in working one kind of ore, the same pockets will be entirely ineffective when operating with or working 50 on another kind of ore or material. I find that these difficulties can be overcome by having the openings or pockets independently adjustable in width, so that each may be made of a size adapted to the requirements of the 55 work. This adjustability may be obtained in various ways. One simple means shown in the drawings is to make the cross-partitions d , which separate the pockets, independently movable and adjustable in the direction of the length 60 of the chamber. To this end they are shown supported by side pins or flanges, d' , which rest in longitudinal guide-grooves d^2 , formed at each edge of the opening in the floor, in which the partitions are placed. The parti- 65 tions are shown in Fig. 3 as quite near together. This, however, is because of the contracted size of the sheet in which the drawing is made.

In practice the openings are wider and are separated by more of an interval from one another. From each pocket the granular material received therein falls into a separate compound screen, E , of any known and approved construction, in which the particles are separated by size. The compound screen shown in the drawings is a horizontal and laterally-vibrating one, formed of a number of superposed wire screens—the coarsest at the 70 top, and each of those below successively being finer than the one above it. Motion is imparted to it by means of a crank-pin, e , working in a longitudinally-slotted arm or bracket, f , attached to the screen, the crank-pin being on a shaft, g , driven from the main shaft h , which, through suitable intermediaries, as shown, actuates the various moving parts of 75 the apparatus.

In order to direct the current of mixed air and ore over the separating or gravity pockets D , and to prevent it to some extent from spreading, I place a wire box-screen, F , around the 80 nozzle and over the pockets, said screen forming in effect the sides and top of a chamber within the main or exhaust chamber D' . Feed-worms or conveyers g' may be placed lengthwise of the floor of chamber D' , outside of the 85 wire-screen chamber F , to carry such material as may sift through the sides of F to the discharge end of the exhaust-chamber D' . At this point in the chamber D' is a like conveyor, h , which carries out therefrom the material received from conveyers g' as well as that portion of the material which is too light to fall in time to be caught in the pockets D .

It will be seen that in this machine I have the parts entirely under control, means being 90 provided whereby I can at will regulate the blast, the feed, and the exhaust, and adjust the size of the gravitating openings or pockets. I am thus enabled to alter the adjustments so that one machine can be made to answer for 95 operation on or working all kinds and varieties of ores and other minerals or materials, and so that the machine can in working any given material be set to effect with the greatest accuracy and precision the separation of that material into sub-groups of any desired character.

What I claim as new and of my invention is as follows:

1. The improvement in the art of separating ores and other materials which consists in carrying and forcing the entire material in granular form, by means of an air-blast, through a nozzle, whence it is blown over a series of separate openings or pockets, substantially as and for the purposes hereinbefore set forth. 105
2. In machinery for separating or concentrating ores and other materials, the combination of the blower or air forcing apparatus, the air-duct leading therefrom, and the ore-feeding device communicating with and opening into 110 said air-duct at a point intermediate between its nozzle or discharge end and the blower, substantially as and for the purposes hereinbefore set forth. 125
3. In machinery for separating or concentrating ores and other materials, the combination of the blower or air forcing apparatus, the air-duct leading therefrom, and the ore-feeding device communicating with and opening into 130 said air-duct at a point intermediate between its nozzle or discharge end and the blower, substantially as and for the purposes hereinbefore set forth.

3. In machinery for separating or concentrating ores and other materials, the combination of a blower or air-forcing apparatus, an air-duct leading therefrom into an exhaust-chamber, an ore-feed device communicating with and opening into said air-duct at a point intermediate between its nozzle or discharge end and the blower, and a series of separate ore-receiving pockets arranged on or in the floor of the exhaust-chamber, substantially as and for the purposes hereinbefore set forth.

4. The feed-hopper and rotating feed-worm therein, in combination with the blower, the air-duct and its discharge nozzle, and the separate ore-receiving pockets or openings, under the arrangement and for operation as herein shown and set forth.

5. The combination, substantially as hereinbefore set forth, of the air and ore discharge nozzle with the exhaust-chamber, provided with openings for admission of air and means

for closing the same more or less as required, and the ore-receiving pockets formed on or in the floor of said chamber and adjustable in width, substantially as and for the purposes hereinbefore set forth.

6. The combination, substantially as hereinbefore set forth, of the blower, the air-duct and its discharge-nozzle, the ore-feed device, the exhaust-chamber, the ore-receiving pockets adjustable in width, and means, substantially as described, whereby the communication of said blower and exhaust-chamber with the surrounding air can be varied at pleasure, substantially as and for the purposes specified.

In testimony whereof I have hereunto set my hand this 29th day of June, A. D. 1881.

ELIJAH WARNE.
